UNITED STATES PATENT OFFICE.

ALBERT H. DE VOE, OF ELIZABETH, NEW JERSEY, ASSIGNOR TO THE SINGER MANUFACTURING COMPANY, A CORPORATION OF NEW JERSEY.

CHAIN-STITCH SEWING-MACHINE.

1,151,513.

Specification of Letters Patent. Patented Aug. 24, 1915.

Application filed January 31, 1908. Serial No. 413,553.

To all whom it may concern:

Be it known that I, ALBERT H. DE VOE, a citizen of the United States, residing at Elizabeth, in the county of Union and State of New Jersey, have invented certain new and useful Improvements in Chain-Stitch Sewing-Machines, of which the following is a specification, reference being had thereto to the accompanying drawings.

10 This invention relates to an improvement in that class of sewing machines in which loops of upper thread are passed through the fabric by means of an eye-pointed needle and are enchain'd by means of a suitable looper or thread-carrier with loops of lower thread upon the lower face of the fabric; and it relates more particularly to machines of such class provided with a plurality of 15 needles and a corresponding number of co-operating loopers for the simultaneous production of a plurality of parallel double-chain-stitch seams.

Heretofore, mechanism of such character as commercially used in the production of 20 the double-chain-stitch, has involved the employment of a threaded looper entering and carrying a loop of its thread through each loop of upper thread presented to it by the needle and retaining the needle-loop 25 thereon during the rise and subsequent descent of the needle to offer the succeeding upper-thread loop. It has thus been necessary to defer the drawing up of each needle loop until its release by the looper after 30 the descent of the needle to carry the succeeding needle-thread loop through the locking looper-thread loop presented for entrance of the needle, which necessitated the reeving of the needle-thread, not only 35 through the needle-eye, but through the last two made needle-punctures and around the intermediate portion of fabric, for the drawing up of the loop still to be set, which endangers, in turn, the cutting out of the 40 needle-punctures in thin goods and renders liable the leaving of loose loops of needle-thread beneath the upper face of the fabric.

Among the several objects of the present invention are,—the production of double-chain-stitch seams of which the needle thread loop of each stitch is set prior to the beginning of a succeeding stitch-forming operation; to obviate the retardation of the needle-loop-forming operation by the wrapping of component thread-loops of a pre-

vious stitch around the needle as it rises to present its loop to the looper; to utilize only so much lower thread as is necessary to form and spread the lower-thread loops for passage of the needle, so as to reduce to a minimum the length of slack under thread to be handled in setting the stitch; to facilitate the threading of the under-thread handling devices, especially as applied to multiple needle and looper machines; and to otherwise increase the effectiveness of machines constructed for production of the double-chain-stitch.

The invention consists essentially in a reciprocating thread-carrying needle and a co-operating non-threaded looper with means for presenting a lower thread to the latter to enable it to pass loops of lower thread through the needle loops, in conjunction with certain additional upper and lower thread handling devices for insuring the proper production and setting of the upper and lower thread-loops successively.

Some attempts have heretofore been made to form a stitch comprising enchain'd loops of upper and lower thread by the employment of a hooked looper passing through the needle loops and seizing bights of lower thread which were drawn through the needle-loops, but so far as I am aware, the present improvement is the first embodiment of such expedient in a successful machine capable of commercial operation.

The form of looper which I prefer to employ is one having a short blade with a point formed as a needle-loop seizing beak behind and above which is an upwardly and laterally inclined under-thread-engaging barb or beard. The blade of the looper first passes through a loop of upper-thread presented by the needle and then its barb seizes a strand of lower thread and draws it through the upper-thread loop preparatory to the shedding of the latter, the drawing up of which forms the bight of lower thread into a loop hanging from the under side of the material which is carried forward by the barb of the looper and is spread for the succeeding descent of the needle through the same. On the rise of the needle for passage of the looper-beak through its thread-loop, the barb sheds the lower-thread loop which is set as the looper advances through the needle-loop to again seize a bight of under thread.

The character of the movement which I prefer to give to the looper is one of reciprocation in a slightly curved path substantially upon the needle-loop seizing side of the needle but extending from a point in advance of the needle path forwardly in an initially rather abrupt curve in the general direction of feed of the fabric and at a slight inclination thereto toward the loop-presenting side of the needle, and the loop-seizing movements of the looper are preferably derived from looper-actuating mechanism constituting a modification of that of the well-known Singer No. 52 single-chain-stitch machine represented in the United States patent to P. Diehl and W. R. Houghton, No. 579,223, dated March 23, 1897, while the side-wise looper movements for insuring the seizure of the lower thread are derived from a link connection between a crank-arm upon the looper rock-shaft and a fixed stud carried by the machine frame. As in the patent referred to, the looper-actuating mechanism comprises practically a combination of two pairs of toggle-levers through which, arranged in successive order, the looper derives its rocking movements from the main-shaft, the effect of which is to produce rapid operative movements and an intermediate dwell of the looper to hold a thread-loop distended for the subsequent descent of the needle through the same. The present toggle mechanism differs from that of said prior patent in that, whereas the former construction includes one toggle in which the pivotal connection of the component members crosses an imaginary line joining the fulera of their opposite ends, and the pivotal connection of the members of the second toggle approaches but does not cross such imaginary connecting line between their opposite ends, according to the present improvement both toggles are alike, in that the pivotal connection of their component members crosses the imaginary line joining the fulera of their opposite ends, and the toggles are connected in such relation that the looper receives a still longer dwell than that produced by the looper-actuating mechanism of the earlier construction.

The present invention includes, in addition to the features above mentioned, certain others to be hereinafter described and pointed out in the appended claims.

In the accompanying drawings, Figure 1 is a front side elevation, and Fig. 2 a bottom plan of a sewing machine embodying the present improvements, and Fig. 3 is a rear side elevation of the machine with the forward portion in section to expose certain constructive features. Fig. 4 is an end elevation of the machine with the face-plate and the operative parts below the bed-plate omitted. Fig. 5 is a sectional elevation

taken on the line $x-x$ of Fig. 2, looking rearwardly, and Fig. 6 a similar view upon the same section line but looking forwardly. Fig. 7 is a detached perspective view of the toggle mechanism employed in the actuation of the looper, and Fig. 8 a detached side elevation of the rearward end of the looper rock-shaft and its link connection with a fixed stud from which it derives its endwise reciprocatory movements. Figs. 9 and 10 are enlarged sectional elevations of the bed-plate and parts beneath the same representing the lower thread-handling devices and the needle in different stages of the stitch-forming operation. Fig. 11 is a perspective view of the stitch-forming devices, Fig. 12 a perspective view of the spreaders acting in conjunction with the loopers, and Fig. 13 a detached elevation of the lower-thread nipping device. Fig. 13^a is a perspective view of one of the thread-nipping members. Fig. 14 is an enlarged perspective view of one of the loopers, and Fig. 15 is a plan of the same showing the manner of its initial engagement of the looper-thread. Fig. 16 is a perspective view of the throat-plate. Fig. 17 is a perspective view of the lower side of the feed-dog showing the thread-guide fingers attached thereto. Fig. 18 is a sectional elevation and Fig. 19 a plan of the slack-controller for the needle-thread.

The machine is constructed with a frame comprising the usual bed-plate 1 and overhanging bracket-arm 2 in which is journaled the main-shaft 3 having at its rearward end the balance-wheel 4 and at its forward end the crank-disk 5 carrying the crank-pin 6 connected by means of the link 7 with the lateral stud 8 carried by the collar 9 fixed upon the needle-bar 10 which is journaled in suitable bushings in the forward portion of the bracket-arm and receives through such connections with the main-shaft its usual reciprocating movements. As herein shown, the needle-bar is provided with a multiple needle-clamp 11 having sockets to receive the shanks of the needles 12 which are secured therein by means of the fastening-screws 13 beneath which are the usual thread-guiding holes 14 through which the needle-threads α are led to their respective needles. As herein shown, the needles are spaced at varying distances apart.

As represented herein, the under side of the bed-plate is provided with fixed bearing lugs 15 and a movable bearing lug 16 which, with its slotted foot 17 secured to the bed-plate intermediate the ways 19 by means of the screws 18, forms an adjustable bracket, the bearing lugs 15 and 16 receiving and carrying the longitudinally arranged looper rock-shaft 20.

The rock-shaft 20 is provided at its rearward end intermediate the bearing lugs 15 with a fixed collar 21 having a lateral crank-

arm terminating in a ball 22 embraced by the strap 23 of a short link 24 provided at its other extremity with a ball 25 which is in turn embraced by a strap 26 at the lower end of a forwardly inclined vertically adjustable screw-stud 27 depending from a boss 28 upon the under side of the bed-plate. The collar 21 is provided with a second upwardly extending crank-arm 29 carrying a ball-crank-pin 30 embraced by a strap 31 at one end of a link 32 having its opposite end embraced by the forked lower end of an upwardly extending link 33 which is in turn embraced by the forked laterally extending 10 rocking arm 34 with fixed fulcrum-pin 34^x, such members being connected together by means of the common pivotal pin 35. The link 33 is forked at its upper end to embrace the lateral arm 37 of a bellcrank-lever to which it is attached by means of a pivotal pin 36, the bellcrank lever having a fixed fulcrum afforded by a pin 38 mounted within the bracket-arm and having an upwardly extending arm 39. The arm 39 is pivotally connected by means of a pin 40 with the forked outer end of the toggle link 41 whose 20 forked inner end is embraced by the forked end of the toggle-link 42 pivotally mounted in the bracket-arm by means of the fulcrum-pin 43 supported in the bearing lugs 43^x of the bracket-arm, the toggle link 41 receiving within its fork the lower end of the pitman 44 connected therewith and with the toggle-link 42 by means of the common pivotal pin 45 and having at its upper end the strap 46 to embrace the actuating crank 47 upon the main-shaft 3.

As will be readily seen, the links 41 and 42 constitute a toggle which is actuated 10 from the crank 47 of the main-shaft through the pitman 44, while the link-members 32 and 34 constitute a second toggle deriving its actuations from the first-mentioned toggle through the bellcrank 37 39 and link 45 33 and imparting rocking movements to the looper-shaft 20 through the pivotal connection of the link 32 with the crank-arm 29 of the fixed collar 21.

Preferring particularly to Fig. 8, it will 50 be observed that the lug 27 constitutes a thrust member against which the link 24 acts in the vertical movements of the crank-pin 22 mounted upon the rock-shaft to cause the latter to have a slight endwise reciprocatory movement as it oscillates through the action of its double toggle connection with the actuating crank 46 of the main-shaft.

The looper rock-shaft carries upon its forward end the looper-carrier, herein shown 60 comprising a sleeve 48 fixed thereon by means of a set-screw 49 and provided with an upwardly extending arm or plate 50 terminating in a cross-bar 51 formed with an angular groove or channel 52 having a flat bottom parallel with the looper-shaft and

an overhanging lip 53 affording a flat seat in substantially radial relation to the looper-shaft, the cross-bar 51 constituting the fixed member of a looper-clamp or holder. Fitted to a suitable inclined seat of the cross-bar 70 channel and secured thereto by means of fastening screws 54 is a cap 55 extending forwardly toward the lip 53 so as to nearly close the top of the channel and provide in its edge adjacent the lip 53 with a series 75 of spaced open slots adapted each to receive the shank portion 56 of a looper having enlarged lower end 57 with an offset 58 extending beneath the lip 53 of the clamp. The cap 55 constitutes the removable member 80 of the clamp, serving to removably secure the base of the looper-shank firmly in place, while its several slots securely maintain the loopers in fixed spaced relation each 85 to the others and to the supporting rock-shaft.

As represented in Figs. 14 and 15, each looper is provided with a blade having convergent flattened sides 59 and 60, the former 90 extending nearly straight to the point of the needle-loop seizing beak 61, while the latter is bulged outwardly intermediate the shank and the beak 61. The top of the looper-blade is formed with a flattened portion 62 over which projects from the forward extremity the backwardly extending barb or beard 63 which is both upwardly and laterally inclined in the direction of the portion 60. Between the open throat 95 of the barb 63 and the point of the beak 61, upon the same side as the flattened portion 60, is a lateral groove 64 adapted to receive the lower thread *b* presented for seizure by the looper, as represented in Fig. 15, and as 100 will be hereinafter more fully described.

Attached to the bottom of the cross-bar 51, by means of screws 65 are thread-guiding arms 66 corresponding in number with the loopers and each provided at its outer 105 end with a self-threading eye 67 having its thread-engaging end disposed below and upon the opposite side of its respective looper from the needle-path, whereby the looper-thread *b* led through the same upwardly 110 through the needle-hole 68 in the throat-plate 69 may cross the path of movement of the barb 63 of the looper to insure the engagement of the lower thread in the retraction of the looper in withdrawing from the loop of upper or needle-thread, as represented particularly in Figs. 11 and 15.

As represented herein, the looper-carrier plate 50 is provided with a recess in which is secured by means of a fastening screw 70 the shank 71 of a double-armed thread controlling member of which one arm 72 carries a laterally extending take-up bar 73 having vertical notches in its opposite ends entered 125 by the down-turned extremities of a transverse guard wire 74, a threading space being 130

provided intermediate the down-turned ends of the guard wire and the notches in the bar 73 for the easy introduction of the threads while locking them against accidental release 5 in the operation of the mechanism. The second arm 75 of the said two-armed member is also provided with a transverse thread-engaging bar 76 having upturned ends to confine the under threads led over the same 10 from the source of lower-thread supply to the looper-mechanism, for which it serves as a pull-off.

Intermediate the pull-off and take-up bars 76 and 73, respectively, is disposed the 15 thread-clamp or nipper, herein represented as adapted for engaging independently a plurality of lower threads. The thread nipping device is shown herein comprising a pair of supporting arms 77 each secured by 20 means of a fastening screw 78 upon the bottom of the thread-cavity 79 formed in the top of the bed-plate and extending along the forward edge of the same, each of such supporting arms carrying at its outer end a block 80 forming the upper member or jaw 25 of a thread-clamp. Each of the blocks 80 is provided at the thinner opposite ends with vertical fins 81 entering the thread-slots 82 in the ends of the reflexly bent spring clamping-plate 83 having its lower member 83^x hung from the block 80 by means of a pin 84 passing through said block with its head 85 disposed within a countersink 86 in the upper portion of the block (Fig. 9). As 30 represented in Fig. 13, the adjacent faces of the clamping members 80 and 83 are beveled at the ends to admit of threading more freely, and the fins 81 are by preference correspondingly beveled at their lower ends for 35 a like purpose, the threading slots 82 of the plates 83 being sufficiently wide to freely admit the looper threads between their edges and the fins 81 while being locked between the members 80 and 83 by such fins. As will 40 be observed, the sustaining pin 84 serves to maintain the looper-threads *b* separated as they pass between the clamping members 80 and 83.

The intermittent action of the movable 45 clamping member 83 upon the lower threads is produced by the engagement upon their yielding lower portions 83^x of the upwardly extending points of the screws 87 tapped at intervals through the cross-bar 88 of a rock-lever 89 fulcrumed intermediate its ends at 50 90 upon the bearing lug 16 and having at its opposite end a slot 91 to receive a lateral pin 92 carried by the feed-lifting bar 93 upon the end of the rock-shaft 94 which has 55 at its rearward end the usual lateral arm 95 having a pitman connection 96 with the feed-lifting crank 97 of the main-shaft 3.

As represented in the United States patent to M. Henleb, No. 863,533, dated August 65 1907, the feed-bar 98, pivoted at its rear-

ward end by means of the pin 99 to the feed-rocker arms 100 extending upwardly from the rock-shaft 101, is supported near its forward end by a link-rod 102 having its opposite ends seated in sockets provided therefor, 70 respectively, in the members 93 and 98, and maintained yieldingly in such relation by means of the connecting spring 103. The feed-bar carries the feed-dog 104 having the usual serrated feeding surfaces entering the 75 feed apertures 69^x in the throat-plate 69 to engage the lower face of the fabric. The feed rock-shaft 101 is provided with the lateral crank-arm 105 pivotally connected with the lower end of the link-bar 106 forked at its 80 upper end to embrace the slide-block 107 fitted to the feed-actuating eccentric 108, the bar 106 being fulcrumed at 109 upon the free end of a link 110 which is in turn fulcrumed at 111 upon the inner arm of the 85 feed adjusting bellcrank lever 112 common to a wellknown style of Singer sewing machine. It will be observed that, while the feed-dog is in lowered or inoperative position, the lifting bar 93 acts through the rock-lever 89 to maintain the thread-clamp closed, and that the thread-clamp is temporarily opened to permit the free passage of the under-thread only during the action of the feed-dog to advance the material. 90

As will be observed from a reference to the drawings, the lower side of the feed-dog beneath its feeding surfaces is notched to form a seat for a multiple thread-guiding plate 113 secured thereto by means of fastening screws 114 and provided with a series of spaced forwardly projecting guide-fingers 115 each disposed upon the needle-loop presenting side of the needle-path and slightly below the needle-hole, in order that the lead 100 of the lower threads between the guide-eyes 67 and the needle-hole 68 may be at such an inclination as to insure the seizure of such thread by the point of the barb 63. 105

Journalized in the bearing lug 16 above 110 the looper rock-shaft 20 for endwise reciprocation, is a spreader rod 116 having secured upon its rearward end a depending arm 117 forked at its lower end to embrace a grooved collar 118 secured by means of a 115 set-screw 119 upon the looper rock-shaft 20. The rod 116 carries at its forward end an upwardly extending arm 120 which carries the forwardly extending spreader supporting bar 121 parallel with the looper rock-shaft and formed with a series of notches in its upper face in which are secured the correspondingly shaped shanks 122 of the wedge-shaped spreader fingers 123 corresponding in number with the loopers, each 120 of which is disposed parallel with the point 61 of its respective looper. The connection of the rod 116 with the looper rock-shaft causes the latter to partake of the endwise movements of the latter without receiving 125

the lateral movements of the loopers, whereby the spreaders coöperate with the loopers in a manner to be hereinafter described in spreading both the upper and under thread-loops.

The plate 50 of the looper-carrier is provided near the sleeve 48 with oppositely projecting thread-guiding pins 124 formed in their outer ends with notches which are substantially radial in relation to the shaft 20, to receive the thinner pins 125 projecting from the sleeve 48 and entering the outer ends of such notches by which they are loosely embraced with sufficient clearance to permit the entrance of the lower threads 5 in threading while retaining the same securely locked therein in the operation of the machine. Each of the fastening screws 78 is utilized in securing in position upon the foot of the supporting arm 77 a pair of guide-eyes 126 at the forward end of the thread-cavity or channel 79 in the rearward end of which is located a thread-guide having a foot portion 127 with an upturned lip 128 formed with guide-eyes 129 into which the threads are threaded through slits 130 extending into the same from the upper edge of the said lip. Upon the bed-plate at the rearward end of the channel 79 is secured a similar thread-guide 131 formed with eyes 132 entered by threading slits 133. The thread-cavity or channel 79 is closed at the top by means of a cover-plate 134 connected to the front edge of the bed-plate by means of the hinges 135.

Upon the needle-bar is adjustably secured by means of a set-screw 136 a collar 137 formed with a lateral take-up arm 138 having a thread-slot 139 to receive the needle-threads from the series of thread-eyes 140 carried by the bracket 141 whose foot is formed with a slot 142 entered by the fastening screw 143 to permit of its vertical adjustment upon the bracket-arm 2.

At the rearward end of the bracket-arm is secured by means of the fastening screws 144 a bracket 145 carrying the oppositely extending threaded pins 146 to each of which is applied a pair of tension-disks 147 and a spring 148 with a nut 149 for maintaining the pressure of the spring upon the outer tension-disk. Adjacent the bracket 145 is a controller-plate 150 containing a series of cylindrical sockets 151 to each of which is fitted a thread-engaging plunger 152 whose stem 153 passes through said socket and carries at its lower end a stop-collar 154. The stem of each plunger is surrounded by a spring 155 interposed between the bottom of the plunger and the bottom of its socket, whereby the plunger is normally maintained yieldingly in raised position, as indicated in Fig. 18. Each of the plungers 152 is formed with longitudinal diametrically arranged grooves to re-

ceive the adjacent edges of a series of flat guide-fingers 156 embracing the plungers and secured by means of fastening screws 157 within suitable slots in the upper portion of the plate 150. At opposite sides of the controller-plate 150 are adjustably secured by means of screws 158 the parallel guide-plates 159 and 160 each provided with a series of thread-guiding slits 161 extending upwardly from its lower edge and corresponding in number with the plungers 152 of the thread-controller.

In the use of the machine as fitted with four needles and four loopers for the production of four parallel double-chain-stitch seams, the four needle-threads are drawn from their respective sources of thread supply, and led each through one of the pairs of tension disks 147, thence through a guide-slit 161 of the thread-guide 159, thence above one of the controller plungers 152 intermediate the pair of guide-fingers 156, through one of the guide-slots 161 of the guide 160 to one of the guide-eyes 140 from which it is passed through the thread-slot 139 of the take-up arm 138 and thence downwardly through one of the guide-holes 14 of the needle-clamp to the eye of one of the needles 12. The four looper-threads are similarly led from their sources of supply each through its respective eye in the guide 131, thence through the corresponding eye of the guide 128 to the guide-eye 126 at the forward end of the thread-cavity 79, whence it is passed over the pull-off bar 76, through one side of its respective thread-clamp, over one of the take-up bars 73, and under the corresponding guide bar 124, through the guide 67, to the needle-hole 68 in the throat-plate 69, through which it emerges, as represented in Fig. 11. To facilitate the threading of the lower threads, the forward portion of the throat-plate is provided with a series of threading slits 68 each leading from its front edge into one of the needle-holes, so that, upon the withdrawal of the bed-plate slide 162 preparatory to the above described threading operation, the passing of the looper-threads from the guide-eyes 67 upwardly through the bed-plate opening in advance of the throat-plate enables the operator to readily pass the same through the threading slits 68 into their respective needle-holes 68 to maintain the proper lead of the lower thread for seizure by the looper in the production of the first stitch. To provide convenient access for passing the lower threads from the guide-member at the base of the bracket-arm to the looper mechanism, the cover-plate 134 is raised as indicated in Fig. 10.

The cover-plate 134 having been shut to close the thread-cavity 79, and the opening above the looper mechanism closed by the

bed-plate slide, the presser-foot 163 is lowered upon the material *m* introduced over the throat-plate and the machine is started. As the needles begin to rise after their first descent, the needle-loop formed by each is entered by the point of its respective looper, and as the needle continues to rise the looper continues to advance in a curved path somewhat inclined to the direction of feed, the point 61 of the looper passing upon the needle side of the looper-thread *b* leading from the guide-eye 67 to the needle-hole and the bulge of the looper at 60° deflecting the looper-thread in addition to the action thereon produced by the inclined path of movement of the looper. Just before the looper reaches the end of its advance movement, the looper-thread, which is maintained taut, snaps over the laterally projecting point of the barb 63, as represented in Figs. 10 and 15. The looper immediately begins its return movement, its taper form causing not only the distention of the needle-loop but the drawing of the same backwardly over the wedge-shaped spreader-finger 123 so as to further enlarge the loop to insure the withdrawal of the looper-blade without its catching upon the point of the barb 63, which at this point retains the bight of looper-thread in its throat. As the point of the looper backs out of the needle-loop, the respective thread-controlling plunger 152, which has been depressed by the pull of the thread intermediate the needle and the tension, is permitted to rise under the action of its spring 155 to draw up the slack needle-thread thus produced, so as to form the bight of lower thread still held by the looper into a closed loop, the opposite end of which is drawn up to the under face of the material, the continued retraction of the looper and its sidewise return movement to initial position with the spreader causing it to draw such loop over the point of the spreader to distend it in advance of the needle-hole for the passage of the needle in its succeeding descent. Meanwhile, the rise of the needle, which continues until the looper is returned to initial retracted position, causes its take-up arm to act upon the needle-thread to set the needle-thread loop.

As the needle reaches its highest point, the feed-dog rises under the action of the lifting bar 93, and the work receives its feeding movement, which causes the previously set needle-loop to advance across the needle-hole so as to incline the lower-thread-loop still retained by the barb of the looper in a favorable position for the succeeding descent of the needle a stitch-length behind the upper end of the distended lower-thread loop. Simultaneously with the advance of the feed-dog the looper is given a slight advance movement under the peculiar timing of its actuating mechanism, which

causes the lower thread-loop to be advanced bodily with the material instead of being further enlarged, as would be the case were the looper to remain stationary until its succeeding loop-taking movement. The needle 70 now makes its second descent through the lower thread-loop, and just before reaching its lowest point the looper again moves backwardly to initial retracted position, but the pull thus produced upon the lower 75 thread-loop, causing its further slight enlargement, is ineffective in disturbing the previously set needle-loop, as would have been the case had this enlargement of the lower thread-loop taken place while the needle was 80 elevated, for the reason that the needle-thread extending from the previously set needle-loop to the needle-eye is now wrapped around the material intermediate the first and second needle punctures, whereby sufficient 85 friction is exerted upon such portion of the needle-thread to insure its remaining as originally set. As the looper moves forward to seize the loop thrown out by the needle in rising, it casts off the lower thread-loop which is drawn up around the needle as the looper advances through the newly formed needle-loop under the action of the take-up and thread-guiding members 73 and 67, respectively, the thread-nipper having 90 been firmly closed upon the thread by the lowering of the feed-dog through the action of the rock-lever 89.

As will be observed, the forward motion of the looper-carrier, which causes the above described operative movements of the thread-engaging members 73 and 67, also produces a corresponding movement of the pull-off bar 76, which acts intermediate the thread-clamp and thread-eye 126 to draw off 105 sufficient lower thread for the succeeding stitch. The timing of the feeding mechanism is such that the point of the adjustable contact screw 87 carried by the rock-lever 89 impinges upon the lower spring member of 110 the clamp-plate 83 only while the feed-dog is in practically its lowest position, which is while the looper is making its forward or needle-loop seizing movement, and it will thus be seen that as the looper returns to its 115 extreme retracted position, in which the lower thread-loop is drawn over the spreader and otherwise expanded as before described, the lower-thread is free to be drawn through the thread-clamp to supply 120 sufficient slack for the purpose, so that the final expansion of the lower thread-loop after the feed has taken place produces very little tendency to distend the previously set needle-thread-loop binding its upper end to 125 the under face of the work.

It will be observed that the lateral movement of the looper away from the needle-path is accompanied by a like movement of the thread-guide eye 67, but that that of the 130

looper is much greater in proportion to its distance from the needle-hole, so that the tendency of the thread-eye 67 in its advance position is to lay the portion of under 5 thread extending from the same, to the needle-hole in the groove 64 extending between the looper point 61 and the throat of the barb 63; and this tendency is materially increased by the employment of the 10 thread-guiding fingers 115 carried by the feed-dog, which are located still more closely to the looper than the lower end of the needle-holes 68, and thus increase the inclination of the lower thread in relation to the path 15 of movement of the looper.

One of the advantages derived from the present improvement, which is of special importance in connection with high-speed-machines, is the short stroke of the needle-bar permitting the employment of a short needle. This is due to the prompt release of the upper and lower thread loops by the looper and their immediate drawing up to the under face of the material, whereby the 20 needle is enabled to descend without the close wrapping around it of previously formed and enchain'd thread-loops, as in double chain-stitch machines heretofore constructed, necessitating a material rise of the 25 needle to partially strip such enwrapped thread-loops by contact with the under face of the fabric to permit the throwing out of the new loop of upper-thread confined to the blade of the needle by such 30 previously formed and enchain'd thread-loops.

As will be observed, particularly by reference to Fig. 14, the bulge of the looper-blade somewhat rearward of the upper- 40 thread loop-seizing point and substantially beneath the barb or beard affording the lower-thread loop-seizing beak, gives a taper form to the looper-blade which, in the return movement constituting the second stage of 45 the excursion of the looper from initial retracted position forwardly and backwardly to the same position constitutes an upper-thread loop-detaining portion which insures the drawing of the needle-loop backwardly 50 upon the point of the spreader to distend the same sufficiently to obviate any liability of the catching of such upper-thread loop by the backwardly extending barb or lower-thread 55 loop-seizing beak in the withdrawal of the looper-blade from such distended upper-thread loop.

As will be observed from the drawings, in its retracted position, the throat of the lower-thread loop-seizing beak 63 of the 60 looper is almost directly in front of the needle-path, in order that the lead of the lower-thread loop held by it in such position may be directly in advance of the needle-hole to enable the needle to descend through 65 the middle of such loop; while the sidewise

movement of the looper in its advance to seize a needle-thread loop is intended to insure the proper presentation of the lower thread leading from the thread-guiding eye 67 under the thread-guard finger 115 to the 70 needle-hole 68 across the blade of the looper so as to be deflected slightly by the looper barb in its advance to cause it to snap under the point of the same into the lateral groove 64 for engagement with such barb on the return of the looper in completing its excursion from initial retracted position. 75

While it is not essential that the thread-guard fingers should be mounted upon a movable part of the machine, it is desirable that they should be carried by the feeding member, as the latter is lowered at the time the lower-thread loop-seizing beak seizes a bight of lower thread, whereby the thread-guard deflects the lower thread leading to the needle-hole to its lowest position to insure the lead of the lower thread across the looper path for such operation. 85

The machine as above described is readily adapted for simultaneous production of 90 seams of different number and spacing by the mere substitution of different thread handling devices, including needle-clamps and looper-clamps. No change whatever in the stationary parts is of course necessary 95 in the application of needle-clamps accommodating different numbers of needles, but in order to obviate any unnecessary overhang of the forward end of the looper rock-shaft, while providing for the application 100 thereto of looper-carriers of different lengths, the forward looper shaft-bearing bracket is made longitudinally adjustable, so that it may be shifted to accommodate any looper-carrier of a given length. While 105 this adaptation of the machine for different numbers and spacings of needles and loopers is not particularly intended to provide the operator with means of adjustment of the gage of the machine, it is of material advantage in the original fitting of the machine, as a single frame may be used for all gages 110 and numbers of needles and loopers by proper selection and application thereto of 115 the special parts required.

From the foregoing description, it will be seen that the present improvement is susceptible of modification of the form and arrangement of the several operative parts in a large degree, and that the invention is not therefore to be understood as limited to the particular embodiment shown and described herein.

Having thus set forth the nature of the invention, what I claim herein is:—

1. In a sewing machine, the combination with needle mechanism including a reciprocating needle carrying an upper thread, of looper mechanism comprising a looper formed with a lower-thread seizing beak 120 130

and an adjacent throat and coöperating with said needle and actuating means therefor to cause it to seize a lower thread, to pass loops thereof through thread loops presented by 5 the needle, and to disengage itself from the lower thread preparatory to seizure of each upper-thread loop.

2. In a sewing machine, a work-support, stitch-forming mechanism comprising a reciprocating needle carrying an upper 10 thread, actuating means for said needle, a non-threaded looper coöperating with said needle and formed with an under-thread seizing beak and an adjacent throat, a 15 thread-guide through which the under thread is led across the looper-path to the lower face of the work, and actuating means whereby said looper is caused to enter each thread-loop presented by the needle and 20 carry through the same a looper-loop and to release the latter before the succeeding seizure of the lower thread.

3. In a sewing machine, a work-support, stitch-forming mechanism comprising a reciprocating needle carrying an upper 25 thread, actuating means for said needle, a non-threaded looper coöperating with said needle and formed with an under-thread seizing beak and an adjacent permanently 30 open throat, a thread-guide through which the under thread is led across the looper-path to the lower face of the work, and actuating means whereby said looper is caused to enter each thread-loop presented by the 35 needle and carry through the same a lower-thread loop and to release the latter before the formation of the succeeding lower-thread loop.

4. In a sewing machine, a work-support, stitch-forming mechanism comprising a reciprocating needle carrying an upper 40 thread, actuating means for said needle, a reciprocating non-threaded looper coöperating with said needle and formed upon the 45 side adjacent the work-support with an under-thread seizing beak and an adjacent permanently open throat, a thread-guide through which the under thread is led across the looper-path and intermediate the 50 latter and the work-support to the lower face of the work, and actuating means whereby said looper is caused to cross the needle-path at one point only and to enter each thread-loop presented by the needle 55 and carry through the same a lower-thread loop.

5. In a sewing machine, a work-support, stitch-forming mechanism comprising a reciprocating needle carrying an upper 60 thread, actuating means for said needle, a thread-guide through which an under thread is led to the work, a looper coöperating with said needle in a path of movement intersecting the position occupied by 65 said under thread and formed with an open-

throated beak for seizing and carrying a loop of lower thread through a needle-thread loop, and means for reciprocating said looper whereby the lower-thread loop is released thereby in the advance movement 70 succeeding a needle-thread loop-shedding retrograde movement.

6. In a sewing machine, a work-support, stitch-forming mechanism comprising a reciprocating needle carrying an upper 75 thread, actuating means for said needle, a non-threaded looper adapted to enter thread-loops presented by said needle and having a lower-thread seizing beak with an adjacent open throat disposed on the side 80 thereof adjacent the work-support during the advance of the looper through the needle-thread loops, a thread-guide through which the under-thread is led intermediate the looper and the work-support to the lower 85 face of the work, and actuating means for imparting operative movements to said looper.

7. In a sewing machine, stitch-forming mechanism comprising a reciprocating 90 needle carrying an upper thread, actuating means for said needle, a non-threaded looper coöperating with said needle and formed with an under-thread seizing beak and an adjacent throat, a thread-guide operatively 95 connected with the looper and adapted to derive therefrom operative movements proportionate to those of the looper and to present the under thread for seizure by the looper, and actuating means whereby said 100 looper is caused to enchain lower-thread loops with the upper-thread loops presented by the needle.

8. In a sewing machine, stitch-forming mechanism comprising a reciprocating 105 needle carrying an upper thread, actuating means for said needle, a non-threaded looper coöperating with said needle and formed with an under-thread seizing beak and an adjacent throat, a carrier upon which said 110 looper is mounted, a thread-guide mounted upon said looper-carrier and adapted to present the under thread for seizure by the looper, and actuating means whereby said looper is caused to enchain lower-thread 115 loops with the upper-thread loops presented by the needle.

9. In a sewing machine, stitch-forming mechanism comprising a reciprocating eye-pointed needle carrying an upper thread, 120 means for reciprocating said needle, a non-threaded looper having a blade formed at one end with an upper-thread seizing beak and upon the upper side with a lower-thread seizing beak, means for effecting the presentation of the lower thread for seizure by the looper, and mechanism for imparting to the looper a reciprocating movement adjacent the needle-path to cause the looper to perform a complete excursion, including an 130

advance lower-thread loop-shedding and upper-thread loop-seizing movement and a retrograde lower-thread loop-seizing and upper-thread loop-shedding movement.

5 10. In a sewing machine, stitch-forming mechanism comprising a reciprocating eye-pointed needle carrying an upper thread, means for reciprocating said needle, a non-threaded looper having a blade formed at one end with an upper-thread seizing beak and upon the upper side with an oppositely directed and upwardly inclined lower-thread seizing beak, means for insuring the presentation of the lower thread for seizure by the 15 looper, and mechanism for imparting to the looper a reciprocating movement adjacent the needle-path to cause the looper to perform a complete excursion, including an advance lower-thread loop-shedding and upper-thread loop-seizing movement and a retrograde lower-thread loop-seizing and upper-thread loop-shedding movement.

11. In a sewing machine, stitch-forming mechanism comprising a reciprocating eye-pointed needle carrying an upper thread, means for reciprocating said needle, a non-threaded looper having a blade formed at one end with an upper-thread seizing beak and upon the upper side with an oppositely directed and upwardly and laterally inclined lower-thread seizing beak, means for insuring the presentation of the lower thread for seizure by the looper, and mechanism for imparting to the looper a reciprocating movement adjacent the needle-path to cause the looper to perform a complete excursion, including an advance lower-thread loop-shedding and upper-thread loop-seizing movement and a retrograde lower-thread loop-seizing and upper-thread loop-shedding movement.

12. In a sewing machine, a stitch-forming mechanism comprising a reciprocating eye-pointed needle carrying an upper thread, a throat-plate having a needle-hole, means for reciprocating said needle through said throat-plate, a non-threaded looper having upper and under thread loop-seizing beaks and movable in a path adjacent that of the needle beneath the throat-plate, means for effecting the presentation of a lower thread for seizure by the looper, a loop-spreader disposed intermediate the throat-plate and looper and adjacent the needle-hole, and actuating mechanism for reciprocating the looper to enter a loop of upper thread presented by the needle and draw a loop of lower thread through the same and upon the spreader for passage of the needle.

60 13. In a sewing machine, a stitch-forming mechanism comprising a reciprocating eye-pointed needle carrying an upper-thread, a throat-plate having a needle-hole, means for reciprocating said needle through the throat-plate, a non-threaded looper having upper

and under thread loop-seizing beaks and movable in a path adjacent that of the needle beneath the throat-plate, means for effecting the presentation of the lower thread for seizure by the looper, a loop-spreader disposed intermediate the throat-plate and looper and adjacent the needle-hole, actuating mechanism for imparting to the looper endwise reciprocating and sidewise movements to cause it to enter a loop of upper thread presented by the needle and to draw a loop of lower thread through the same and upon the spreader for passage of the needle, and a connection between the looper and spreader whereby the latter is caused to follow the sidewise movements of the looper.

14. In a sewing machine, a stitch-forming mechanism comprising a reciprocating eye-pointed needle carrying an upper thread, a throat-plate having a needle-hole, means for reciprocating said needle through said throat-plate, a reciprocating non-threaded looper having a blade formed with upper and under thread loop-seizing beaks and with an upper thread-loop detaining portion, said looper being adapted to move in a path adjacent that of the needle beneath the throat-plate, means for effecting the presentation of the lower thread for seizure by the looper, a loop-spreader disposed intermediate the throat-plate and looper and adjacent the needle-hole, actuating mechanism for imparting to the looper endwise reciprocating and sidewise movements whereby in its advance movement it enters a loop of upper thread and in its return movement it seizes a bight of lower thread, carries its loop of upper thread upon the spreader and draws the lower thread loop through the same as thus distended and upon the spreader for the succeeding descent of the needle.

15. In a sewing machine, the combination with suitable feeding mechanism and actuating means therefor, of stitch-forming mechanism comprising a reciprocating eye-pointed needle carrying an upper thread, a throat-plate having a needle-hole, means for reciprocating said needle through the throat-plate, a reciprocating non-threaded looper having a blade disposed substantially in the direction of feed and formed with upper and under thread loop-seizing beaks, said looper being adapted to move in a path adjacent that of the needle beneath the throat-plate, means for effecting the presentation of the lower thread for seizure by the looper, and looper actuating mechanism adapted to impart to the looper a complete reciprocation, substantially in the direction of feed, for each reciprocation of the needle, and a supplemental advance movement simultaneously with each feeding movement preparatory to every descent of the needle to present its loop for seizure by the looper, whereby the

looper is caused to advance through an upper-thread loop, seize a bight of lower thread and draw it through said upper-thread loop.

- 5 16. In a sewing machine, stitch-forming mechanism comprising a reciprocating eye-pointed needle carrying an upper thread, a throat-plate having a needle-hole, means for reciprocating said needle through the
 10 throat-plate, a non-threaded looper having a blade formed at one end with an upper-thread seizing beak and upon the upper side with a reversely disposed lower-thread loop-seizing beak and movable in a path adjacent that of the needle beneath the throat-plate, means for effecting the presentation of the lower thread for seizure by the looper, an endwise movable rock-shaft upon which the looper is mounted, means for communicating rocking movements to said rock-shaft for imparting to the looper its endwise loop-seizing and shedding movements and sidewise loop positioning movements, a longitudinally movable loop-spreader disposed above the looper, and a connection intermediate said loop-spreader and the looper-rock-shaft whereby said spreader is caused to follow the sidewise movements of the looper and to serve in the retraction of the
 20 looper to first enter and spread the upper-thread loop carried by the latter, to then operate in conjunction with the lower-thread engaging beak of the looper as a former for the bight of lower thread into a loop and
 25 to finally maintain the lower-thread loop distended for penetration by the needle in its succeeding descent.
17. In a sewing machine, stitch-forming mechanism comprising a reciprocating eye-pointed needle carrying an upper thread,
 30 means for reciprocating said needle, a non-threaded looper having a blade formed at one end with an upper-thread seizing beak and upon the upper side with an oppositely disposed and upwardly and laterally inclined lower-thread seizing beak and with a lateral thread groove extending from the point of the upper-thread beak to the throat of the lower-thread beak upon the side toward which the latter is inclined, means for presenting the lower thread in a line intersecting the path of movement of the lower-thread beak, and mechanism for imparting to the looper a reciprocating movement adjacent the needle path to cause the looper to perform a complete excursion including an upper-thread loop-seizing movement and a return lower-thread loop-seizing and upper-thread loop-shedding movement.
- 35 18. In a sewing machine, stitch-forming mechanism comprising a reciprocating eye-pointed needle carrying an upper thread, means for reciprocating said needle, a non-threaded looper having upper and under-thread loop-seizing beaks, means for effect-
 40 19. In a sewing machine, stitch-forming mechanism comprising a reciprocating eye-pointed needle carrying an upper thread, means for reciprocating said needle, a non-threaded looper having a forwardly extending upper-thread loop-seizing beak and an open-throated backwardly extending lower-thread loop-seizing beak, means for effecting the presentation of the lower thread for seizure by the looper, mechanism for imparting to the looper a reciprocating movement adjacent to the needle-path to cause the looper to alternately enter and enchain loops of upper and lower thread, and to shed during the return movement of the looper the upper-thread loops and the lower-thread loops in the subsequent advance movements of the looper preparatory to seizure of a succeeding upper-thread loop, and means for drawing up the lower thread during the advance movement of the looper intermediate the shedding of said lower-thread loop and the succeeding engagement of the lower thread by the looper.
- 45 20. In a sewing machine, stitch-forming mechanism comprising a reciprocating eye-pointed needle carrying an upper thread, means for reciprocating said needle, an oscillating looper cooperating with said needle in the loop-presenting position thereof in enchain loops of upper and lower thread, and a lower-thread take-up connected with and movable substantially in the direction of lead of the thread at its point of engagement therewith and in a circular path around a single axis of movement coincident with that of said looper and adapted to draw up the lower thread during the advance movement of said looper through a loop of upper thread presented by the needle.
- 50 21. In a sewing machine, stitch-forming mechanism comprising a reciprocating eye-pointed needle carrying an upper thread, means for reciprocating said needle, a looper adapted to seize a lower thread and pass loops thereof through thread-loops presented by the needle, a reciprocating carrier in which said looper is mounted, actuating means for said looper-carrier, and a

- lower-thread take-up rigidly secured upon said looper-carrier and adapted to operatively engage the lower thread in the operative movements of said looper.
22. In a sewing machine, stitch-forming mechanism comprising a reciprocating eye-pointed needle carrying an upper thread, means for reciprocating said needle, a reciprocating non-threaded looper having reversely-directed upper and under loop-seizing beaks and coöperating with said needle in enchaining loops of upper and lower thread, looper-actuating means, a lower-thread nipping device with actuating means therefor to cause it to nip the lower thread while the looper is advancing through an upper-thread loop, and an under-thread take-up with actuating means for causing it to operatively engage the lower thread while the looper is advancing.
23. In a sewing machine, stitch-forming mechanism comprising a reciprocating eye-pointed needle carrying an upper thread, means for reciprocating said needle, a reciprocating non-threaded looper having an upper-thread seizing beak and a reversely directed open-throated lower thread seizing beak and coöperating with said needle in enchaining loops of upper and lower thread, looper-actuating means, feeding mechanism comprising a feed-bar carrying a feed-dog, a feed-rocker connected with said feed-bar, and a feed-lifting rock-shaft having a connection with said feed-bar, actuating mechanism for the feed-rocker and feed-lifting rock-shaft, whereby the feed-dog is lifted and advanced to feed the work while the looper is approaching its extreme advance position, and is lowered and retracted for a fresh engagement with the work during the return movement of the looper, a lower-thread nipping device, an operative connection between said thread-nipping device and the feed-lifting rock-shaft, and a lower-thread take-up.
24. In a sewing machine, stitch-forming mechanism comprising a reciprocating eye-pointed needle carrying an upper thread, means for reciprocating said needle, a reciprocating looper having reversely directed upper and under loop seizing beaks and coöperating with said needle in enchaining loops of upper and lower thread, an oscillating carrier upon which said looper is mounted, looper-actuating means, a lower-thread nipping device with means for actuating it, and under-thread take-up and pull-off devices mounted upon and moving with said looper carrier and adapted to engage the under-thread upon opposite sides of the said nipping device, and operative connections intermediate said take-up and pull-off and the looper whereby they are caused to operate simultaneously and synchronously with the looper.
25. In a sewing machine, stitch-forming mechanism comprising a reciprocating eye-pointed needle carrying an upper thread, means for reciprocating said needle, a looper having reversely directed upper and under loop seizing beaks and coöperating with said needle in enchaining loops of upper and lower thread, a reciprocating carrier in which said looper is mounted, actuating means for said looper-carrier, a lower-thread nipping device with means for actuating it, a two-armed thread-controlling member mounted upon said looper-carrier and embracing said nipping device, a transverse take-up bar carried by one arm and a transverse pull-off bar carried by the other arm of said member and adapted to engage the lower thread upon the opposite sides of said thread-nipping device.
26. In a sewing machine, stitch-forming mechanism comprising a reciprocating needle-bar, and a plurality of eye-pointed needles mounted thereon and each carrying an upper thread, means for reciprocating said needle-bar, a looper rock-shaft and means for actuating the same, a looper-carrier mounted upon said rock-shaft and formed with a cross-bar having an angular channel parallel with said rock-shaft, a looper-clamp member forming a cap for closing said channel at the top and provided in one edge with a series of parallel looper-shank slots opposed to one of the side walls of said channel, means for removably securing said cap in position upon said cross-bar, and a series of loopers having angular shanks fitted to said channel and each inserted in one of the slots of said clamp-member, each of said loopers being adapted to coöperate with its respective needle in the production of stitches.
27. In a sewing machine, stitch-forming mechanism comprising a reciprocating needle-bar, and a plurality of eye-pointed needles mounted thereon and each carrying an upper thread, means for reciprocating said needle-bar, a looper rock-shaft and means for actuating the same, a looper-carrier mounted upon said rock-shaft and formed with a radially extending arm or web carrying a looper-clamp, a plurality of loopers removably secured in said clamp and each adapted to coöperate with its respective needle in the production of stitches, a series of thread-guides and a multiple take-up device carried by said looper-carrier, a guide-pin carried by the radial arm or web of said looper-carrier and extending from both faces of the same and provided in its extremities with radially disposed thread notches, and pins also carried by said looper-carrier and entering and loosely embraced by the notches of said laterally extending guide-pins and affording threading apertures at opposite sides of said radial arm or web.

web for introduction of threads led from said take-up to said thread-guides.

28. In a sewing machine, the combination with stitch-forming mechanism comprising a reciprocating eye-pointed needle carrying an upper thread, a throat-plate having a needle-hole, means for reciprocating said needle through said throat-plate, a non-threaded looper having upper and under thread loop-seizing beaks, and moving in a path beneath the throat-plate adjacent that of the needle, a lower thread-guide below the path of movement of the looper through which the lower thread is led to the needle-hole, a thread-guard spaced beneath the throat-plate and intermediate the needle-hole and said thread-guide for deflecting the lower thread leading from the latter across the path of movement of said looper, and looper-actuating mechanism for causing said looper to alternately engage and enchain the upper and lower threads in the production of stitches.

29. In a sewing machine, the combination with stitch-forming mechanism comprising a reciprocating eye-pointed needle carrying an upper thread, a throat-plate having a needle-hole, means for reciprocating said needle through said throat-plate, a non-threaded looper having upper and under thread loop-seizing beaks, moving in a path beneath the throat-plate adjacent that of the needle, feeding mechanism comprising a feed-dog, a feed-bar carrying the same and means for actuating it, a lower-thread guide below the path of movement of the looper through which the lower thread is led to the needle-hole, a thread-guard carried by the feed-dog beneath the throat-plate and adjacent the needle-hole and looper-actuating mechanism for causing said looper to alternately engage and enchain the upper and lower threads in the production of stitches.

30. In a sewing machine, the combination with stitch-forming mechanism comprising a reciprocating needle-bar having a plurality of eye-pointed needles each carrying an upper thread, a throat-plate having a plurality of needle-holes, means for reciprocating said needles through said throat-plate, a plurality of non-threaded loopers each having an upper and an under-thread loop-seizing beak and moving in a path beneath the throat-plate and adjacent its respective needle, feeding mechanism comprising a feed-dog, a feed-bar carrying the same and means for actuating it, a plurality of lower thread-guides each disposed below the path of movement of one of said loopers through which a lower thread is led to the needle-hole entered by one of said needles, a thread-guard formed of a plate having a series of slots producing a plurality of thread-guiding fingers each disposed adjacent a needle-hole, said thread-guard plate

being secured to and carried by said feed-dog, and looper-actuating mechanism for causing said loopers to alternately engage and enchain the upper and lower threads in the production of stitches.

31. In a sewing machine, stitch-forming mechanism comprising a reciprocating needle-bar, and a plurality of eye-pointed needles mounted thereon and each carrying an upper thread, means for reciprocating said needle-bar, a throat-plate formed with a plurality of needle-holes corresponding in number and spacing with said needles and with a threading slit leading from its front edge into each of said needle-holes, a plurality of non-threaded loopers having upper and under thread loop-seizing beaks, a plurality of thread-guides each adapted to lead a lower thread across the path of movement of its respective looper into one of said needle-holes, and mechanism for imparting to the loopers a reciprocating movement adjacent their respective needle paths whereby they are caused each to perform a complete excursion during the rise of the needles including an upper-thread loop-seizing movement and a return lower-thread loop-seizing and upper-thread loop-shedding movement.

32. In a sewing machine, the combination with a frame comprising a bed-plate and an overhanging bracket-arm, of a main-shaft mounted in said bracket-arm, a needle-bar mounted for vertical movement in said bracket-arm, operative connections between said main-shaft and the needle-bar for reciprocating the latter, a plurality of needles carried by said needle-bar, a fixed shaft-bearing depending from said bed-plate, a longitudinally adjustable bracket depending from said bed-plate and affording a movable shaft bearing, a looper rock-shaft journaled at the rearward end in said fixed bearing and near the forward end in said adjustable shaft-bearing, a plurality of loopers mounted upon the forward portion of said rock-shaft and adapted to coöperate with said needles in the production of stitches, and operative connections intermediate the main-shaft and the rearward portion of said looper rock-shaft for imparting operative movements thereto.

33. In a sewing machine, the combination with a frame comprising a bed-plate and an overhanging bracket-arm, of a main-shaft journaled in said bracket-arm and provided in its rearward portion with a looper-actuating crank, a needle-bar carrying a needle, and operative connections intermediate the forward portion of said main-shaft and needle-bar for imparting vertical reciprocations to the latter, a looper rock-shaft journaled beneath said bed-plate, a looper upon the forward end of said rock-shaft co-operating with said needle in the produc-

- tion of stitches, a crank upon the rearward end of said rock-shaft, a pair of pivotally connected toggle links, one of which is mounted upon a fixed fulcrum and the other 5 is pivotally connected with said crank, a second pair of pivotally connected toggle links of which the one is mounted upon a fixed fulcrum and the other is operatively connected with the first named pair of 10 toggle links at their junction, and a pitman rod affording an operative connection between the junction of the second named pair of toggle links and the actuating crank upon the main-shaft.
- 15 34. In a sewing machine, the combination with a main-shaft, of a needle-bar carrying a needle, operative connections intermediate said needle-bar and the main-shaft, a looper rock-shaft, a looper thereon cooperating 20 with said needle in the production of stitches, a crank upon said looper rock-shaft, two pairs of toggle links of which the extreme end of one of the component links is connected with the junction of the 25 component links of the other pair, while an extremity of one of the component links of the second-named pair is pivotally connected with the said crank upon the looper rock-shaft, and an operative connection intermediate said main-shaft and the pivotal connection of the component links of the 30 first-named pair, whereby the pivotal connections of the component members of both 35 toggle links are reciprocated across the imaginary line joining the extremities of the links of each pair in the actuation of said looper shaft through its connecting crank.
35. In a sewing machine, stitch-forming mechanism comprising a reciprocating eye-
- pointed needle adapted to carry an upper thread, means for reciprocating said needle, a non-threaded looper constructed with a blade having all its parts rigidly connected together in fixed relation and provided with upper and under thread loop-seizing beaks 45 and moving in a path adjacent that of the needle, means for effecting the presentation of the lower thread for seizure by the looper, and looper-actuating mechanism adapted to impart to the looper a complete operative 50 excursion for each reciprocation of the needle for enchainment of a single upper-thread loop with a single lower-thread loop in the production of a double-chain-stitch.
36. In a sewing machine, stitch-forming 55 mechanism comprising a reciprocating eye-pointed needle carrying an upper thread, means for reciprocating said needle, an oscillatory looper comprising a single element and adapted to seize thread loops from said 60 needle and to present loops thereto upon the same side of the work in enchaining loops of upper and lower thread, and a lower-thread take-up connected with and movable in a circular path around the axis 65 of movement of said looper and substantially in the direction of lead of the thread across the same and adapted to draw up 70 the lower thread during the advance movement of said looper through a loop of upper thread presented by the needle.

In testimony whereof, I have signed my name to this specification, in the presence of two subscribing witnesses.
